Primary Examiner — Garth Rademaker*Assistant Examiner* — Llorellys Martinez-Rivera*(74) Attorney, Agent, or Firm* — Sheppard Mullin Richter & Hampton LLP(57) **CLAIM**

I claim the ornamental design for a wristband, as shown and described.

DESCRIPTION

FIG. 1 is a top perspective view of a wristband embodying the new design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken lines shown in FIG. 1 illustrate portions of the wristband which form no part of the claimed design.
